Moses H. Fisher

UNITED STATES PATENT OFFICE.

MAJOR H. FISHER, OF BRIDGEPORT, CONNECTICUT, ASSIGNOR TO THE
FRANKLIN FILE COMPANY, OF SAME PLACE.

IMPROVEMENT IN MACHINES FOR CUTTING FILES.

Specification forming part of Letters Patent No. 37,419, dated January 13, 1863.

To all whom it may concern:

Be it known that I, MAJOR H. FISHER, of the town of Bridgeport, county of Fairfield, and State of Connecticut, have invented a new and Useful Improvement in File-Cutting Machinery; and I do hereby declare that the following description with the accompanying drawings form a full and exact description thereof.

My said invention is an improvement upon the invention heretofore made by me, and patented August 28, 1846; and it consists of an improved method of attaching the chisel to the chisel-arm. It is applicable to the machinery described in said patent, or to any other file-cutting machinery now in use, requiring a chisel arm and holder actuated by shafts and cams or other suitable device. Such machinery, being well known, need not be described.

The accompanying drawings fully illustrate my invention.

Figure 1 is a top view of my chisel arm and holder with the chisel in its place. Fig. 2 is a bottom view of the same. Fig. 3 is a vertical longitudinal section of the same in the line A B of Fig. 1. Fig. 4 is a view of the back side of the chisel.

The same letters refer to the same parts in the several figures.

The chisel-arm *a* is constructed of the same material, and is attached to the machine in the same manner as the one patented to me as assignee on the 5th of February, 1856, and the only material difference between my present invention and that patented in 1856 consists in the manner in which I secure the chisel *E* in the oblique slot *d* of the chisel-arm *a*. Reference may be had to the said patent of 1856, from which the present improvement will fully appear. I now dispense entirely with the sliding chisel-holder *g*, described in the patent of 1856, and with the coiled spring underneath it, having found from experience that they cannot be used to advantage, and that they do not accomplish the desired object. In place of these I attach a steel point, *b*, to the under side of the chisel-arm, which point projects just far enough into the oblique slot of the said arm to fit into the inclined

notch *i* of the chisel when the chisel is placed in its proper position.

The inclined notch *i* on the back part of the chisel, it will be observed, is another new feature. In the patent of 1856 there was merely a round hole or notch, in the chisel, into which the point of the sliding chisel-holder fitted so that the chisel could not rise and fall in the slot of the chisel-arm without carrying the sliding chisel-holder along with it, so that if the sliding chisel holder or the spring underneath it became clogged, as frequently happened, the chisel could not rise or fall independent of the chisel-arm. Between the front side of the chisel *E* and the end of the chisel-arm *a*, I now place a circular spring, *c*, which spring is located partly within the chisel-arm *a*, and projects into the slot of said arm far enough to press against the front side of the chisel. At the end of the chisel-arm *a* is a set-screw, *S*, by means of which the pressure of the spring *c* against the front of the chisel may be increased or diminished as desired.

When the file-cutting machine is ready for operation, the chisel is in the position shown in Fig. 1. As the arm *a* descends the edge of the chisel is brought in contact with the surface of the file-blank, so that when the hammer falls the edge of the chisel is driven downward, and at the same time a little backward, owing to the inclination of the inclined notch *i*. This slight backward motion of the chisel is of the utmost importance, as it gives the proper form to the burr, which cannot be produced in any other manner. As the chisel-arm rises after the stroke of the hammer the file-blank is fed forward, and the pressure of the edge of the chisel against the burr raised by the cut last made is so relieved by the spring *c* that neither the edge of the chisel or of the burr is injured. It will also be observed that by means of the inclined notch, and owing to the manner in which the chisel is held in the chisel-arm, that the chisel has an up-and-down motion, a backward-and-forward motion, and a motion from one side to the other independent of the chisel arm. Thus, when the chisel descends and touches the file-blank, the edge readily accommodates itself to the sur-

face of said blank, and when the hammer falls the chisel is driven downward and backward, while the chisel-arm itself remains stationary.

Having thus described my invention, what I claim therein as new, and desire to secure by Letters Patent, is—

1. The inclined notch *i* in the chisel.

2. The adjustable spring *c*, in combination with the notch *i*, substantially as and for the purposes described.

MAJOR H. FISHER.
